UNITED STATES PATENT OFFICE.

EMMET ALPHA DEAN, OF OAK PARK, ILLINOIS, ASSIGNOR TO WESTERN ELECTRIC COMPANY, INCORPORATED, OF NEW YORK, N. Y., A CORPORATION OF NEW YORK.

ELECTRICAL INSULATOR.

Application filed September 28, 1923. Serial No. 665,269.

This invention relates to electrical insulators, and more particularly to insulators employed with electrical currents of high voltages.

5 Where insulators are used to insulate conductors carrying, or which may be subjected to, electrical currents of high voltages, it is desirable that the insulation afforded thereby be reliable under all operating conditions in order to properly protect the associated apparatus and the operators attending the apparatus. Any moisture which may collect on the electrical insulating material, such as by condensation from the 15 surrounding atmosphere, may provide a leakage path for the electrical current present in the conductors associated therewith, which path may in some instances, especially when high voltage currents are employed, materially lessen the insulation resistance of 20 the insulator. Sometimes due to a reduction in the temperature of the surrounding atmosphere moisture condenses therefrom upon the surface of the insulator, which 25 deleteriously affects the insulating quality of the insulator.

Although it is desirable to maintain unimpaired the dielectric strength of the electrical insulator, in all cases it is of especial 30 importance in connection with high voltage transmission lines, and high voltage circuits for testing the insulation resistance and capacitance of electrical apparatus.

An object of the invention is to maintain 35 unimpaired the efficiency of an insulator during a reduction in temperature.

Another object is to prevent the formation 40 of leakage paths on the exposed surface of an electrical insulator.

45 A further object is to shroud a body of electrical insulating material with a heat conduction material, such as metal, which will tend to condense the moisture in a humid atmosphere.

50 An electrical insulator made in accordance with one embodiment of the invention may comprise a body of insulating material, such as hard rubber, surrounding or otherwise supporting an electrical conductor, and which in turn may be surrounded by a spaced shrouding member of metal, such as brass.

These and other features of the invention not specifically mentioned will clearly ap-

pear from the following description and the 55 accompanying drawings, in which

Fig. 1 shows a longitudinal view, in section, of an electrical insulator surrounding the conductor and associated with a clamp type of mounting; 60

Fig. 2 is a transverse section taken along the lines 2—2 of Fig. 1;

Fig. 3 is an elevation, partially in section, of a modified form of the insulator shown in Figs. 1 and 2. 65

Referring to the drawings, in which similar reference characters are employed to denote similar parts throughout the various figures, a rod 10, of copper or other material suitable for the conduction of electrical current is surrounded by an insulating tube 11, preferably of hard rubber. Tube 11 may be attached to the rod 10 by means of a pin 12, the ends of which may be covered by any suitable insulating compound. However, this method of attachment is not essential, in fact in some cases no attachment may be necessary. The rod 10 is threaded at either end to receive pairs of nuts 15 adapted to clamp therebetween electrical terminals 70 16, which may be connected by leads 18 and 19 to an electrical circuit (not shown) so that current may flow over one of the leads through the conducting rod 10 and return over the other lead. 75

80 A metal sheath 20, preferably of brass, surrounds the tube 11 but is slightly shorter than the tube and is attached thereto by means of a screw 21. The exterior diameter of the tube 11 is reduced near its ends to 85 provide an annular space between the tube and the shrouding sheath 20. Cap or petticoat members 23 and 24 are loosely mounted upon the ends of the rod 10, being secured in position between the ends of the tube 11 90 and the associated nuts 15, and having walls extending inwardly beyond the ends of the sheath 20. The assembled insulator may be mounted in a vertical or horizontal position upon a metal member 27, which although 95 only partially shown, may be suitably attached in any manner desired to a support. A clamping member 26, together with bolts 100 28 and nuts 29 cooperate to secure the insulator in place upon the member 27. However, this means of support is not essential and any other form of mounting may be 105 employed if desired. When the insulator

is mounted in a vertical position, it may be desirable to add a petticoat 30, preferably of rubber, which covers and prevents the entrance of foreign matter into the open end 5 of the cap member 24 as shown in Fig. 3.

It is well known that a good conductor of heat, such as brass or other metal, responds more quickly and accurately to changes in temperatures than a poor conductor of heat, 10 such as hard rubber. Therefore, when brass and hard rubber articles are placed closely adjacent to each other so as to be simultaneously subjected to a reduction in temperature, the moisture which may be condensed 15 from the surrounding atmosphere will collect upon the relatively cool brass article, while the surface of the relatively warmer rubber article will remain substantially free from moisture. These characteristics of the 20 dissimilar materials are employed in the present invention to maintain the insulative qualities of an electrical body unimpaired when exposed to humidity laden atmosphere and subjected to changing temperatures. 25 When the temperature of the atmosphere in which the insulator may be placed begins to fall, the brass shrouding member 20 cools more quickly than the associated enclosed 30 hard rubber insulating body 11. Hence, the moisture which is condensed from the atmosphere, due to the lowering of the temperature, collects on the wall of the metal member, and since the relative temperatures of the 35 metal and the rubber are maintained during further decreases in temperature, it is evident that the surface of the insulating body is maintained free from condensation at all times.

What is claimed is:

- 40 1. An insulating support for an electric conductor requiring a high insulation resistance, consisting of an insulating tube having a central section of larger diameter than the end sections, a conductor passing through 45 the center of the tube, a metallic sheath slightly shorter than the tube surrounding the tube but spaced therefrom a distance insuring the collection upon the interior surface of substantially all moisture condensed 50 from the atmosphere between the exposed portion of the tube and the interior surface

of the sheath, said sheath contacting with the central portion of the tube, a cap covering the end of the sheath in contact with the tube and the conductor but spaced from the 55 sheath, and means for attaching an external conductor to the conductor leading through and supported by the tube.

2. In an electrical insulator, a tube of insulating material having a reduced end portion, an electric conductor surrounded by the tube, a metal sheath attached to and surrounding the tube and having its interior surface parallel to but spaced from the exterior surface of the reduced portion of the 60 tube by a distance insuring the collection upon the interior surface of substantially all moisture condensed from the atmosphere between the exposed portion of the tube and the interior surface of the sheath, and a 65 cap covering the end of the sheath in contact with the reduced end of the tube and the conductor but spaced from the sheath.

3. In an electrical insulator, a metal rod, a rubber tube attached to and surrounding 70 the rod, a metal sleeve attached to and surrounding the rubber tube, the end portions of the tube extending beyond the ends of the sheath and reduced in exterior diameter for a predetermined distance within the sheath 75 so to provide access of atmosphere to the exterior surfaces of such portions and to portions of the interior surface of the sheath therearound, said portions of the interior surface being spaced from the surrounded 80 exterior surfaces of the reduced portions by a distance insuring the selective collection thereon of substantially all of the moisture condensed from the atmosphere between said interior surface and the surrounded exterior 85 surfaces of the reduced portions of the tube, metal caps for surrounding the ends of the sheath, means for securing the caps to and connecting electrical terminals with the rod, and a cap member of insulating material secured to the metal sheath and covering the 90 open end of the lower metal cap.

In witness whereof, I hereunto subscribe my name this 18th day of September A. D., 1923.

EMMET ALPHA DEAN.
